UNITED STATES PATENT OFFICE.

SAMUEL ROTAN, OF BROWNSVILLE, INDIANA, ASSIGNOR OF ONE-HALF TO
JOHN L. RITER, OF SAME PLACE.

FORCE-FEED FOR SEEDING-MACHINES.

SPECIFICATION forming part of Letters Patent No. 255,119, dated March 21, 1882.

Application filed April 5, 1881. (Model.)

To all whom it may concern:

Be it known that I, SAMUEL ROTAN, residing at Brownsville, in the county of Union and State of Indiana, have invented certain new useful Improvements in Force-Feeds for Seeding-Machines; and I do hereby declare the following to be a full, clear, and exact description of the invention, such as will enable others skilled in the art to which it pertains to make and use it, reference being had to the accompanying drawings, which form part of this specification.

This invention relates to certain improvements in seeding-machines of the class known as "force-feeds;" and the objects are to simplify the manufacture of the parts constituting the force-feed, to dispense with the use of hubs or sleeves, and to produce a force-feed at a small cost.

Heretofore in the manufacture of force-feeds for seeding-machines it is usual to cast the fluted feed-wheel with a smooth portion or hub to fit one of the side openings in the feed-cup, or the hub cast independently of the fluted feed-wheel, but united thereto so as to pass through the side opening of the feed-cup. This is objectionable for the reason that it is difficult to cast the two parts so as to fit snugly, owing to shrinkage and roughness of the castings, and the poor fit of the feed-wheel hub in the cup-opening causes an oscillating motion that varies the size of the conduit and produces an irregular or uneven flow of the grain.

My invention therefore consists in the employment of an enlarged tubular shaft, preferably made of gas-pipe, to receive the feed-wheels and the cut-offs.

My invention also consists, in combination with an enlarged hollow cylindrical shaft, of a seed-cup having one of its side bearings of a diameter corresponding with the exterior diameter of the shaft, whereby a snug and close fit is formed, and the space of the conduit between the feed-wheel and the inner face of the bottom of the feed-cup always remains of the same size, thus insuring a continuous and even discharge of the grain from the mouth of the feed-cup.

My invention also consists in the combination with the enlarged tubular shaft, of a fluted

feed-wheel, and a double cut-off mounted and arranged on said tubular shaft, as will be hereinafter described.

My invention also consists in the novel construction of the double cut-offs, as will be hereinafter more fully described. 55

My invention also consists, in combination with a seed-cup having an upper gate, of the cut-off having a groove adapted to engage with the gate of the seed-cup. 60

My invention also consists in the novel construction and combination of parts, as will be hereinafter more fully described, and pointed out in the claims.

Figure 1 of the drawings is a representation of a perspective view of my improved force-feed device. Fig. 2 is a plan or top view of the same; Fig. 3, a vertical sectional view taken through the line $x-x$ of Fig. 2, looking toward the feed-cup. Fig. 4 is a perspective view of a portion of a tubular shaft with a feed-wheel and cut-offs arranged in their respective order. Fig. 5 is a perspective view of the rose-washer. 65

In the annexed drawings, forming a part of this specification, the letter A represents the feed-cup with the usual side openings, constructed in two sections in the usual manner.

The letter B represents a hollow or tubular shaft, made preferably of gas-pipe, the exterior diameter of which is about one inch, so as to fit snugly the smaller side opening in the feed-cup section a' —that is to say, the diameter of this opening of the feed-cup is such as to correspond with the exterior diameter of this tubular shaft. By making the shaft hollow and of gas-pipe a smooth surface is produced to fit the opening of a corresponding diameter in the feed-cup with little or no fitting, whereas when both feed-cup and hub or sleeve are made of cast metal, owing to the shrinkage and roughness of the castings, much time is consumed in fitting the parts to a nice adjustment; also, by making the shaft tubular the time in drilling the holes for the passage of the fastening-pins is materially lessened, and strength with lightness is secured. Upon this hollow shaft (see Fig. 4) is arranged a fluted feed-wheel, D, with a smooth extension, b, through which are bored registering-holes to 100

receive the fastening-pin J' , that secures the feed-wheel to the shaft, and the cut-offs c c' are also mounted on this shaft, so as to face the feed-wheel, and are retained in position on the shaft by means of the fastening-pin J , outside of the collar, as shown. The cut-offs c c' are united to a collar, C , by casting or otherwise. The upper cut-off, c' , is formed with a longitudinal groove, c^2 , for a purpose about to be stated. This upper cut-off, c' , formed with the longitudinal groove c^2 , when applied to the tubular shaft and adjusted in the feed-cup, passes under and fits the sides of the gate f , formed in the feed-cup, substantially as seen in Figs. 1 and 3 of the drawings, and its office is to aid in holding the cut-offs in their relative positions in the feed-cup. This construction of the cut-offs united to the collar C is to obviate an existing difficulty in casting the feed-cup with a groove in the gate to receive an upper cut-off; but by transferring the groove to the cut-off, as herein described and shown, the feed-cup section, with the gate, is now easily withdrawn from the sand of the mold. This section of the feed-cup is also formed with an angular notch to receive the lower cut-off, c , as seen in Fig. 3 of the drawings.

It will be observed by reference to Fig. 4, showing the fluted feed-wheel D and the cut-offs mounted and fastened on the tubular shaft in the order shown, that I am enabled to dispense with the hub or sleeve that usually accompanies a force-feed of this class; also, by this novel organization the force-feed works full in the grain or seed, which comes in contact with both the face and edge of the feed-wheel.

The letter E represents a rose-washer (see Fig. 5) which fits and works into a formed recess in the section a of the feed-cup, and is provided on its inner face with a series of ribs or arms, e , of a length less than the space from the flutes and outer edge. The object of arranging these ribs or arms upon the inner face of the rose-washer E , substantially as seen in Figs. 1 and 5 of the drawings, is to have them act in conjunction with the longitudinal ribs upon the fluted feed-wheels, for the purpose of making a combined horizontal and vertical feed. This rose-washer is also provided with the usual notches, corresponding in number and size with the flutes on the feed-wheel.

The tubular shaft with its attachments, the fluted feed-wheel, and cut-offs are adjusted to the feed-cup, substantially as seen in Fig. 1, the feed-wheel having its bearings in the rose-washer E and the tubular shaft fitting the bearings in the side opening of the feed-cup section a' . The hollow shaft, thus fitting the bearings in the section a' of the feed-cup, forms a conduit or space in the bottom of the feed-cup, between the fluted feed-wheel and the inner face of the bottom of the feed-cup, of a size that will always remain the same, thereby insuring a continuous and even discharge of the grain from the mouth of the feed-cup.

The cut-off c , it will be observed, operates in the bottom of the feed-cup and extends from its collar C nearly to the end of the fluted feed-wheel D , to prevent the bruising of the grain on the edge feed, and from the hollow shaft to the inner face of the bottom of the feed-cup. As the fluted feed-wheel D has a lengthwise movement in and out through the rose-washer E , the cut-off c follows the fluted feed-wheel and its movement regulates the quantity of grain to be sown. The cut off c' , attached to the same collar C , fills the space in the upper part of the feed-cup, between the hollow shaft and the gate f of section a of the feed-cup.

The lip or mouth of the discharge-orifice of the feed-cup is inclined or oblique—that is to say, it is higher on the side a' of the feed-cup than it is on the side a of the feed-cup. Hence, as the grain is forced forward in the bottom of the feed-cup, it is forced toward the rose-washer and discharged over the lip or mouth of the feed-cup at or near the inner face of the rose-washer. Hence, as the fluted feed-wheel D forces the grain forward over the lip or mouth of the feed-cup, the ribs or arms on the rose-washer act as distributors in causing an even and continuous discharge of the grain or feed from the feed-cup.

As the fluted feed-wheel D has a lengthwise movement through the rose-washer E , it is evident that the quantity of grain to be sown to the acre will be determined from the section of the fluted feed-wheel operating in the feed-cup.

The seed-cups will be attached to the bottom of the feed-box, and the tubular shaft passing through the seed-cups will be revolved by gear-wheels and revolve therewith, the feed-wheels and rose-washers to elevate and discharge the grain through the elevated mouth.

I am aware that it is not broadly new in seeding-machines to employ a hollow or tubular shaft upon which are mounted grain-feed wheels; but

What I claim as new, and desire to secure by Letters Patent, is—

1. In a force-feed seeding-machine, the combination of an enlarged tubular shaft working in contact with the grain and a feed-wheel, substantially as described.

2. In a force-feed seeding-machine, the combination of an enlarged tubular shaft working in contact with the grain, a feed-wheel, and cut-offs, substantially as set forth.

3. In a force-feed seeding-machine, the combination of a feed-cup having side openings and an elevated discharge-orifice, an enlarged tubular shaft passed through the side openings of the feed-cup and working in contact with the grain, a fluted feed-wheel, and upper and lower cut-offs, substantially as described.

4. In a force-feed seeding-machine, the combination of a feed-cup having a side opening or passage and an enlarged tubular shaft with an exterior diameter fitting closely the said

opening or passage of the feed-cup and revolving in contact with the grain, substantially as set forth.

5. In a force-feed seeding-machine, the combination of the feed-cup, the enlarged tubular shaft with the fluted feed-wheel fitted thereon, the independent cut-offs, and a rose-washer, said parts being arranged for operation substantially as described.
10. 6. In a force-feed seeding-machine, the cut-offs consisting of the collar C, the lower cut-

off, c, and upper cut-off, c', with the longitudinal groove c², substantially as shown and described.

In testimony that I claim the foregoing as my invention I have hereunto set my hand this 1st day of April, 1881.

SAMUEL ROTAN.
